United States Patent Office

Des. 225,617
Patented Dec. 26, 1972

225,617

BOTTLE

Kenji Hanamura, Tokyo, Japan, assignor to Tancho Co.,
Ltd., Higashi-ku, Osaka, Japan

Filed Feb. 9, 1971, Ser. No. 114,102

Term of patent 14 years

Int. Cl. D9—01

U.S. Cl. D9—169

FIG.1

FIG.2

FIG.3

FIG. 1 is a top plan view of a bottle showing my new design;

FIG. 2 is an elevational view thereof; and

FIG. 3 is a bottom plan view thereof.

The container is symmetric, and the elevation view is the same from all directions.

I claim:

The ornamental design for a bottle, as shown and described.
